UNITED STATES PATENT OFFICE.

JOHN S. PECK, OF PITTSBURG, AND HARVE R. STUART, OF WILKINSBURG, PENNSYLVANIA, ASSIGNORS TO WESTINGHOUSE ELECTRIC & MANUFACTURING COMPANY, A CORPORATION OF PENNSYLVANIA.

VOLTAGE-REGULATING APPARATUS.

SPECIFICATION forming part of Letters Patent No. 740,173, dated September 29, 1903.

Application filed October 13, 1902. Serial No. 127,154. (No model.)

To all whom it may concern:

Be it known that we, JOHN S. PECK, residing at Pittsburg, and HARVE R. STUART, residing at Wilkinsburg, in the county of Allegheny and State of Pennsylvania, citizens of the United States, have invented a new and useful Improvement in Voltage-Regulating Apparatus, of which the following is a specification.

10 Our invention relates to apparatus employed for raising or lowering the voltages of alternating-current circuits; and it has for its object to provide simple and efficient apparatus for this purpose which shall be 15 adapted for use in cases where the currents are so large or the voltages are so high that they cannot be safely handled by the regulators ordinarily employed in such service.

Our invention is illustrated in the accompanying drawings, in which—
20 Figures 1, 2, 3, and 4 are diagrammatic illustrations of different forms of regulating apparatus.

It is usual to employ an adjustable switch-25 ing device for varying the active length of either the primary or the secondary winding of a transformer in order to vary the electro-motive force of the secondary circuit; but it is difficult or impossible to obtain satisfac-30 tory results with apparatus of this character, particularly where the currents are very large or the voltages are very high, without making a greater number of divisions of the winding, the active length of which is to be 35 varied, than is practicable. It is also a usual practice to vary the voltage of an alternating-current circuit by means of a regulator which acts inductively by making one of the mem-40 bers movable with reference to the other, and thus adjusting the polar relations of the two members. Such apparatus is, however, ex-45 pensive and can only be operated by the expenditure of a considerable amount of power, from which it follows that a more simple and 50 easily-operated device is desirable, provided such a device can be made effective and durable.

Our invention meets these requirements and will now be described in detail, reference 55 being first had to Fig. 1 of the drawings, in

which the working or distributing circuit 12 is supplied by the secondary 3 of a transformer 4, the primary 3^a of which is supplied by a circuit 5 6 and is provided with a series of spaced leads 7, which severally terminate in contact-terminals 8, mounted upon a suitable base 9. Pivotaly mounted upon the base 9 are two switch-arms 10 and 11, which are respectively so mounted as to make successive engagement with the contact-terminals 8 60 and are respectively connected through a suitable reversing-switch 12 to the terminals of the primary winding 13 of an auxiliary transformer 14, the secondary winding 15 of which is included in the conductor 6 of the primary 65 or supply circuit. It will be seen that this arrangement of apparatus and circuits is such that the winding 13 of the auxiliary transformer 14 may be connected across different lengths of the primary winding 3^a of the trans-70 former 4, so that different voltages are impressed upon the said winding 13, with the result that a varying voltage is obtained on the winding 15 and also upon the primary 3^a of the main transformer, which in turn causes a variation 75 in voltage on the secondary 3. The reversing-switch is employed in order to increase the range of voltage variation to double the amount which would be possible without its use. It is to be understood, however, that 80 the reversing-switch is not an indispensable feature of our invention, and it is to be further understood that a switching device having a single arm 9 or 10 will serve our purpose satisfactorily and be within the scope of 85 our invention.

While a simple adjusting-switch is shown for varying the active length of the winding 3^a of the main transformer with reference to the auxiliary transformer and a separate reversing-switch is indicated, these two devices may in practice be made parts of a single regulator, as is indicated, for example, in Patent No. 607,617, granted July 19, 1898, to the Westinghouse Electric & Manufacturing 90 Company as assignee of H. P. Davis and G. Wright, and the structural details of the regulator may be such as the designer or user 95 may desire.

In Fig. 2 the conductors 1, 2, 5, and 6, the 100

transformer 4, its windings 3 and 3^a, and the reversing-switch 12 are or may be the same as the corresponding parts shown in Fig. 1. The regulating-switch is here shown, however, as having a single arm 10^a for cooperating with the contact-terminals 8, and this arm is connected through one side of the reversing-switch with one terminal of the primary winding 13^a of the auxiliary transformer 14^a, the other terminal of the winding 13^a being connected through the reversing-switch with conductor 6 of the main primary circuit. The secondary winding 15^a of the auxiliary transformer 14^a has a plurality of spaced leads 16, which extend to corresponding contact-pieces 17 on the base 9^a. When the contact-arm 10^a is in engagement with the outer or first contact-terminal of the set 17, both ends of the primary winding 13^a of the transformer 14^a are connected to the outer terminal of the secondary winding 15^a, and the auxiliary transformer is therefore inactive. As the arm 10^a is moved into engagement with the successive contact-terminals of the set 17 one terminal of the winding 13^a is brought into electrical connection with the corresponding points in the winding 15^a, whereby the voltage impressed upon the winding 3^a is correspondingly raised or lowered, according to the position of the reversing-switch. As the movement of the arm 10^a is continued the transferable terminal of the winding 13^a is connected to the successive leads 7, whereby a variable electromotive force is impressed upon said winding, and this reacts upon the winding 15^a in substantially the manner already described.

In Fig. 3 the apparatus is the same as that illustrated in Fig. 1, and the several parts are designated by the same reference-numerals, except as will be presently pointed out, and reference may be had, therefore, to the description of such parts which has already been given in lieu of repeating the same. In this organization of apparatus the winding 15^b of the auxiliary transformer 14^b is located in the secondary circuit of the main transformer in series with the main-transformer secondary winding and the other winding 13^b of the auxiliary transformer is connected to the proper contact-terminals of the reversing-switch 12, so that it may be connected across different portions of the primary winding of the main transformer as the arms 10 and 11 or either of them are moved to make engagement with different contact-terminals 8.

In Fig. 4 the apparatus is the same as in Fig. 3, except that the winding of the auxiliary transformer 14^c which is included in series with the secondary of the main transformer 4 is made in two parts 18 and 19, the former of which is included in the conductor 2 and the latter of which is included in the conductor 1 of the secondary circuit, the other winding 13^c being connected the same as the corresponding winding in Fig. 3. With this

arrangement of circuits the secondary voltages are symmetrical with reference to any fixed point in the secondary winding of the transformer—as, for example, the middle point—so that if a third conductor 20 be connected to the middle point, as indicated, a balanced three-wire circuit is provided.

As has already been indicated, the regulating apparatus and system here illustrated and described may be used in connection with a constant-potential source of energy in order to provide a variable voltage, or it may be used in connection with a source of variable potential and be utilized to deliver it at either a constant or a variable voltage or for obtaining a constant current from a constant-potential circuit. The invention is also applicable to polyphase as well as single-phase circuits.

We claim as our invention—

1. In a voltage-regulating apparatus, the combination with a main transformer having one of its windings provided with leads extending from different points thereof and an auxiliary transformer having one of its windings in series with one of the main-transformer windings, and an adjustable switching device for connecting the terminals of the other winding of the auxiliary transformer with different leads from the main-transformer winding.

2. In a voltage-regulator, the combination with a main transformer one of the windings of which is provided with a plurality of leads and an auxiliary transformer having one winding in series with one of the windings of the main transformer, of a switching device for connecting the other winding of the auxiliary transformer in series with any desired portion of the length of one of the main-transformer windings.

3. In a voltage-regulating apparatus, the combination with a main transformer having one of its windings provided with leads extending from different points thereof and an auxiliary transformer having one of its windings in series with one of the main-transformer windings, of a reversing-switch connected to the other winding of the auxiliary transformer and an adjustable switching device for connecting the reversing-switch terminals with different leads from the main-transformer winding.

4. In a voltage-regulator, the combination with a main transformer one of the windings of which is provided with a plurality of leads and an auxiliary transformer having one winding in series with one of the windings of the main transformer, of a switching device for connecting the other winding of the auxiliary transformer in series with any desired portion of the length of one of the main-transformer windings and a switch for reversing the terminal connections of the last-mentioned auxiliary-transformer winding.

5. In a voltage-regulator, the combination with a main transformer one of the windings

of which has a plurality of spaced leads, of an auxiliary transformer having its windings connected together at one end, one of said windings having a plurality of spaced leads, 5 and a switching device comprising contact-terminals for all of said leads and a co-operating, movable, contact-terminal.

6. In a voltage-regulator, the combination with a main transformer one of the windings 10 of which has a plurality of spaced leads, of an auxiliary transformer having one of its windings connected in series with one of the windings of the main transformer and means for connecting either of the terminals of the 15 other winding of the auxiliary transformer to any one of the spaced leads of the main-transformer winding.

7. In a voltage-regulator, the combination

with a main transformer one of the windings of which has a plurality of spaced leads, of 20 an auxiliary transformer having one of its windings connected in series with one of the windings of the main transformer, means for connecting one of the terminals of the other auxiliary winding to any one of the spaced 25 leads of the main-transformer winding and means for reversing the terminals of said auxiliary winding.

In testimony whereof we have hereunto subscribed our names this 7th day of October, 1902.

JOHN S. PECK.
HARVE R. STUART.
